Specification for Design.

Patented Feb. 22, 1916.

Application filed January 9, 1915. Serial No. 1,470. Term of patent 14 years.

To all whom it may concern:

Be it known that I, LOUIS CARL PEDLAR, a citizen of the United States, residing at 517 West One Hundred and Thirteenth street, in the borough of Manhattan and State of New York, have invented a new and original ornamental Design for an Ornamental Shield, of which the following is a specification, reference being made to the accompanying drawings, forming a part thereof.

Figure I is a view in elevation of my

improved ornamental shield, and Fig. II is an edge view thereof.

I claim:

The ornamental design for an ornamental shield substantially as illustrated.

In testimony whereof, I affix my signature in the presence of two witnesses.

LOUIS CARL PEDLAR.
